UNITED STATES PATENT OFFICE

119,357

DESIGN FOR A DRESS ENSEMBLE

Sabina De Pasquale, New York, N. Y.

Application January 29, 1940, Serial No. 89,824

Term of patent 3½ years

To all whom it may concern:

Be it known that I, Sabina De Pasquale, a citizen of the United States, residing in New York city, in the county of New York and State of New York, have invented a new, original, and ornamental Design for a Dress Ensemble, of which the following is a specification, reference being had to the accompanying drawing, forming part thereof.

Fig. 1 is a front view of a dress ensemble showing my design;

Fig. 2 is a rear view of Fig. 1;

Fig. 3 is a front view of the dress member of the ensemble shown in Fig. 1, and

Fig. 4 is the rear view thereof.

The characteristic feature of my design resides in the combination on the ensemble disclosed the specific bolero member which is embroidered as shown in association with the matching embroidery on the pockets of the dress member.

I claim:

The ornamental design for a dress ensemble, substantially as shown and described.

SABINA DE PASQUALE.
